SMOKE BOX STRUCTURE

Le Roy Thompson, Blakely, Ga., assignor to Locomotive Economizer Corporation, New York, N. Y., a corporation of Delaware

Application May 20, 1944, Serial No. 536,465

4 Claims. (Cl. 230—97)

This invention relates to locomotive smoke box structures and is concerned more particularly with a novel smoke box structure which includes means for preventing incandescent cinders from being discharged from the smoke stack. The new structure eliminates the fire hazard that would arise from the presence of live cinders in the discharge and it accomplishes its intended function without loss of locomotive efficiency. At the same time, it permits easy access to the interior of the smoke box for inspection, cleaning, and testing purposes.

In my Patent No. 2,104,958, issued January 11, 1938, I disclosed a smoke box structure for eliminating live cinders from the stack discharge of a locomotive and the patented structure includes partition means within the smoke box for directing the gases of combustion in their travel from the rear end of the smoke box to the stack. The partition means define passageways including louvre plates extending across the path of flow of the gases in such fashion that live cinders borne along by the gases impinge upon the plates at maximum speed and are broken up as a result of such impingement. In the patented structure, there is a bank of louvre plates lying transversely of the smoke box and the bank of plates extends from the bottom of the smoke box to a point near the top of the usual inspection door opening in the front wall of the smoke box. The gases traveling forwardly through the smoke box pass along opposite sides of the partition means and then reverse their direction of travel and pass between the louvres mentioned. In addition, some of the gases may flow between louvre plates in opposite walls of the partition means adjacent the stack. This arrangement has proven highly effective for the purpose but the bank of louvre plates at the front end of the smoke box cuts off ready access to the space inside the partition, within which lies the injection nozzle. Accordingly, when this space is to be inspected or cleaned or the injection nozzle is to be capped for testing purposes, the bank of louvres at the forward end of the smoke box must be removed.

The present invention is directed to the provision of a novel smoke box structure which serves the same purposes and produces the same results as that disclosed in the patent but is so arranged that access to the injection nozzle and the space around it can be had through the door at the front end of the smoke box without the removal of any parts.

For a better understanding of the invention,

reference may be had to the accompanying drawings, in which

Fig. 1 is a vertical longitudinal sectional view through the smoke box of a locomotive on the line 1—1 of Fig. 2;

Fig. 2 is a horizontal longitudinal view on the line 2—2 of Fig. 1; and

Fig. 3 is a transverse vertical sectional view on the line 3—3 of Fig. 1.

In the construction illustrated in the drawings, the smoke box includes the usual casing 10 which is mounted on the forward end of the locomotive boiler. The front end wall 11 of the boiler forms the rear wall of the smoke box and the boiler flues open into the smoke box through wall 11. At its forward end, the smoke box is closed by a front wall 12 having a central opening closed by a hinged inspection door 13. A stack extension 14 extends downwardly through the top of the smoke box into the interior thereof and an injection nozzle 15 extends upwardly through the bottom wall of the smoke box in alignment with the stack extension.

The gases issuing from the flues are directed to the stack by partition means including a vertical partition wall 16 which extends from the front wall at one side of the axis of the smoke box backwardly to the rear of the stack extension and then forwardly to the front wall at the other side of the axis of the smoke box. The wall includes front sections 16a, 16b, which lie parallel to one another, intermediate rearwardly convergent sections 16c, 16d, and a rear end section which has the form of the arc of a circle drawn about a center on the axis of the smoke box and of less radius than half the distance between the front sections 16a, 16b. Openings 17 are formed in the lower front corners of the sections 16a, 16b, and through these openings, access may be had to the space within partition 16. The upper ends of the openings 17 lie below the plane of the top of the inspection door 13 and in the construction illustrated, lie somewhat below the center of the door opening. By forming the partition wall with the arcuate rear section 16e and the forwardly divergent sections 16c, 16d ahead of it, the passages along the sides of the partition between it and the inner wall of the smoke box cause the gases issuing from the boiler flues to travel with smooth non-turbulent flow to the openings 17.

A pair of plates 18, 19 extend from the upper edges of the legs of partition wall 16 outwardly to the wall of the smoke box and a plate 20 having a curved upper edge extends upwardly from the

partition wall 16 and the tops of plates 18, 19 at the rear ends thereof to the smoke box shell. A similar plate 21 extends across the smoke box from the upper edges of the front partition sections 16a, 16b and the tops of plates 18, 19 to the wall of the smoke box.

Adjacent the nozzle and stack, the intermediate sections 16c, 16d of the partition 16 are provided with openings elongated vertically and containing banks 22 of vertical louvre plates. Each plate is made up of a pair of flanges lying at right angles to one another and the plates are mounted spaced apart in nesting relation so as to define tortuous passages between adjacent plates.

A plurality of banks of horizontal louvre plates are also mounted around the edges of openings 17 to span the space between the front sections 16a, 16b of partition 16. In the construction shown, there are three banks of such plates, with the lowermost bank 23a extending vertically and the next higher bank 23b extending forwardly at a slight angle to the vertical. The third bank 23c extends downwardly and forwardly from the upper end of the intermediate bank 23b to the plane of the front wall of the smoke box at the lower edge of the inspection door opening. The space between the lower ends of walls 16a, 16b is closed by a partition 24 which may extend from the bottom louvre plate in the lowermost bank 23a to the inner surface of the smoke box wall.

With the construction described, the hot gases of combustion issuing from the boiler flues and entering the smoke box through the rear wall pass forwardly along opposite sides of the partition 16 below the horizontal plates 18, 19 and a portion of the gases may pass through the louvre plates 22 into the space inside the partition and thence into the stack. Other portions of the gases continue forwardly below plates 18, 19 to the opening 17 and then turn inwardly and reverse their direction of flow and pass between the louvre plates of the banks 23a, 23b, 23c into the space within partition 16. As the gases are about to pass through the louvre plates of the several banks, the gases change direction and the cinders borne along by the gases strike the surfaces of the plates. As a result, the cinders are broken up and crushed by the impact and the particles are made smaller, so that when they emerge from the stack, they are no longer incandescent and present no fire hazard.

With the new structure, the interior of the smoke box is readily accessible through the inspection door in the front wall, since none of the banks of louvres mounted along the edges of openings 17 interfere. The total number of louvres in these banks is somewhat less than the total number at the front of the smoke box in the prior construction, but this reduction in the number of louvres and of the total area between them for the passage of gases is counterbalanced by increasing the size of the openings in which louvres 22 are mounted. I have found that these changes in no way impair the efficiency of the locomotive or the effectiveness of the structure as a means for eliminating live cinders and the ease with which access to the interior of the smoke box may be had for inspection and cleaning and capping of the injection nozzle, when the locomotive is to be subjected to hydraulic testing, makes the new structure more advantageous than the prior one.

In the structure disclosed in my patent, the partition means includes a front wall formed of banks of louvre plates extending from the bottom

of the smoke box to a relatively high level above the lower end of the stack extension. With this arrangement, access to the space behind the banks of louvre plates and, in particular, to the injection nozzle, can be had only by removing the banks of plates. With the present arrangement, the front sections 16a, 16b of partition 16 do not have openings adjacent the front wall of the smoke stack which run from top to bottom of the walls; instead, the openings 17 are formed only in the lower front corners of walls 16a, 16b, so that the banks of louvres 23a, 23b, 23c terminate at such a level as to permit ready access into the interior of the casing through the inspection door. The total number of louvres in the banks mounted along the edges of openings 17 is somewhat less than the total number at the front of the smoke box in the prior construction. This reduction in the number of louvres and the spaces between them for the passage of the gases in the new structure is counterbalanced by increasing the size of the openings in which the louvre plates 22 are mounted. I have found that these changes in no way impair the efficiency of the locomotive or the effectiveness of the structure as a means for eliminating live cinders. At the same time, the new arrangement facilitates inspection and cleaning of the interior of the smoke box and the capping of the injection nozzle when the locomotive is to be subjected to hydraulic testing.

I claim:

1. In a locomotive structure including a smoke box having a front end closed by a front wall provided with a central opening closable by a door, and a smoke stack and an injection nozzle arranged in vertical alignment in the top and bottom, respectively, of the smoke box between its front and rear ends, partition means for directing the products of combustion from the rear of the smoke box to the stack and comprising vertical walls extending upwardly from the bottom of the smoke box to above the level of the lower end of the stack, the vertical walls extending around the stack to the rear thereof and forwardly to the front wall of the smoke box at their upper ends, said vertical walls having openings in their front lower corners adjacent said front wall, top walls extending outwardly from the upper edges of the vertical walls to the inner surface of the smoke box, the top walls extending forwardly to the front wall of the smoke box, a transverse partition extending upwardly from the upper edges of the vertical walls at the rear end thereof to the inner surface of the smoke box, louvre plates mounted in openings in the vertical walls at opposite sides of the stack, and louvre plates mounted along the edges of the openings in the lower front corners of the vertical walls and spanning the space between said vertical walls, whereby all gases entering the openings in the corners of the vertical walls pass between louvre plates in their travel to the stack.

2. In a locomotive structure including a smoke box having a front end closed by a front wall provided with a central opening closable by a door, and a smoke stack and an injection nozzle arranged in vertical alignment in the top and bottom, respectively, of the smoke box between its front and rear ends, partition means for directing the products of combustion from the rear of the smoke box to the stack and comprising vertical walls extending upwardly from the bottom of the smoke box to above the level of the lower end of the stack, the vertical walls extending around the stack to the rear thereof and for-

wardly to the front wall of the smoke box at their upper ends, said vertical walls having openings in their front lower corners adjacent said front wall, the tops of the openings lying below the level of the top of the central opening through the front wall of the smoke box, top walls extending outwardly from the upper edges of the vertical walls to the inner surface of the smoke box, the top walls extending forwardly to the front wall of the smoke box, a transverse partition extending upwardly from the upper edges of the vertical walls at the rear end thereof to the inner surface of the smoke box, louvre plates mounted in openings in said vertical walls at opposite sides of the stack, and louvre plates mounted along the edges of the openings in the lower front corners of said vertical walls and spanning the space between said vertical walls, whereby all gases entering the openings in the corners of the vertical walls pass between the louvre plates in their travel to the stack.

3. In a locomotive structure including a smoke box having a front end closed by a front wall provided with a central opening closable by a door, and a smoke stack and an injection nozzle arranged in vertical alignment in the top and bottom, respectively, of the smoke box between its front and rear ends, partition means for directing the products of combustion from the rear of the smoke box to the stack and comprising vertical walls extending upwardly from the bottom of the smoke box to above the level of the lower end of the stack, the vertical walls extending around the stack to the rear thereof and forwardly to the front wall of the smoke box at their upper ends, said vertical walls having openings in their front lower corners adjacent said front wall, top walls extending outwardly from the upper edges of the vertical walls to the inner surface of the smoke box, the top walls extending forwardly to the front wall of the smoke box, a transverse partition extending upwardly from the upper edges of the vertical walls at the rear end thereof to the inner surface of the smoke box, a similar transverse partition extending upwardly

from the top edges of the vertical walls at the forward end thereof to the inner surface of the smoke box, vertical louvre plates mounted in openings in the vertical walls at opposite sides of the stack, and horizontal louvre plates mounted along the edges of the openings in the lower front corners of the vertical walls and spanning the space between said vertical walls, whereby all gases entering the openings in the corners of the vertical walls pass between the louvre plates in their travel to the stack.

4. In a locomotive structure including a smoke box having a front end closed by a front wall provided with a central opening closable by a door, and a smoke stack and an injection nozzle arranged in vertical alignment in the top and bottom, respectively, of the smoke box between its ends, the combination of partition means for directing the products of combustion from the rear of the smoke box to the stack and comprising vertical walls rising from the bottom of the smoke box to above the level of the lower end of the stack, said walls including parallel front sections meeting the front wall of the smoke box at their upper ends and having openings at their lower front corners, rearwardly convergent intermediate wall sections extending from the rear edges of the parallel sections, and a curved rear end section joining the rear ends of the intermediate sections, top walls extending outwardly from the upper edges of said vertical walls to the inner surface of the smoke box, the top walls extending forwardly to the front wall of the smoke box, a transverse partition extending upwardly from the top walls at the rear end of the vertical walls to the inner surface of the smoke box, louvre plates mounted in openings in the intermediate wall sections at opposite sides of the stack, and louvre plates mounted along the edges of the openings in the lower front corners of the parallel wall sections and spanning the space between said wall sections, whereby all gases entering said openings pass between the louvre plates in their travel to the stack.

LE ROY THOMPSON.
